ERASER FEEDING DEVICE

George Findra, New Brunswick N. J.

Application January 5, 1938, Serial No. 183,525

3 Claims. (Cl. 120—36)

This invention relates generally to improvements in mechanical writing instruments and the like and, more especially, to improved means for adjustably holding an eraser in the end portion of a writing instrument.

It is among the more important objects of the present invention to provide a novel means for adjustably holding and at least partially exposing an auxiliary device, for instance an eraser or the like, in an end portion of a writing instrument such as a pencil or a pen, whereby the exposed portion of said auxiliary device can be increased or diminished to suit the needs or wishes of the user.

It is another object of the present invention to provide a novel holding and positive feeding means positionable in an end portion of a writing instrument whereby an auxiliary device can be adjustably supported and quickly and easily adjusted in a position adapted for use and also can be replaced when desired.

Notable among the features of the device according to the present invention are its compactness, relative simplicity of construction, substantial freedom from parts normally subjected to wear, easy adjustability and attractive appearance.

Other objects, advantages and features of the device according to the present invention will be apparent to those skilled in the art during the course of the following description, wherein a specific embodiment of the present invention, herein illustrated, will be described, it being clearly understood however that the illustrated preferred embodiment is given solely by way of example and is non-limitative.

In the drawing:

Fig. 1 is a side elevational view of a writing instrument provided with eraser holding and feeding means according to the present invention;

Fig. 2 is substantially a vertical sectional view of the eraser feeding and holding parts in the device illustrated in Fig. 1; and

Fig. 3 is an exploded perspective view of a preferred form of eraser holding and feeding means.

Regarded in certain of its broader aspects, the present invention comprises a cap-like member 50 slidable within a rotatable substantially cylindrical member positioned in an end portion of a writing instrument, said member being associated whereby rotative movement of said annular member is translated into coaxial sliding movement of said cap member.

In order to facilitate a clear understanding of the matter of the present invention, a specific illustrated embodiment thereof will be herein-after described.

Referring now to the drawing and especially Fig. 1, a pencil or similar writing instrument generally designated at 10 is provided near an end portion thereof with an ornamental friction cap indicated by the numeral 11, said cap preferably being provided with a clip 12, substantially as shown, for the purpose of holding the writing instrument within the user's pocket.

Referring now to Fig. 2, it will be noted that the writing instrument generally designated at 10 includes a casing member 15 provided at an end portion thereof with writing means, in this instance a mechanical pencil unit generally designated at 16. The other, or free, end portion of said casing member 15 serves, in part at least, as a housing for the substantially cylindrical sleeve 17 freely rotatably positioned therein, which projects outwardly therefrom, substantially as shown, and which is adapted to receive and support, on the projecting portion thereof, the cap member 11 hereinbefore alluded to.

The sleeve-like member 17 and its associated and cooperating members provide the novel feeding and supporting means for auxiliary devices forming the subject matter of the present invention. The member 17 is substantially cylindrical in shape, fully open on the projecting end and provided with formations on the other or inner end thereof, generally indicated at 18, which serve to at least mostly close the end thereof. The essentially hollow, tube-like member 19 fixedly attached to and carried on said end portion 18 of the member 17, substantially extends coaxially through the casing 15 and, passing through an opening in the member 20, engages at the projecting free end with a washer 19a, abutting against a part of the opening formed in the member 20, substantially as shown, the last mentioned member being frictionally engaged with the inner surface of the casing whereby relative movement of the members 15 and 20 is at least largely precluded. It will be noted, therefore, that the member 17, though freely rotatable, is anchored within the casing 15 and cannot be moved outwardly therefrom without moving the member 20 or dissociating the members 19, 19a and 20.

In order to prevent inward movement of the member 17 relative to the casing 15, and also to accomplish other results hereinafter to be described, a substantially cylindrical member 21 is

provided, adapted to be positioned circumjacent the tubular member 19, which at one end abuts against a friction reducing washer 23, positioned next to the end part 18 of the member 17, and which is firmly frictionally held at the other end in the constricted portion 24 of the member 20. Accordingly, it will be noted that although the sleeve member 17 can be freely rotated with respect to the casing 15, it (the said member 17) is substantially prevented from moving coaxially within the casing 15, in one direction by the member 21 abutting against the end portion 18 of the member 17 and against parts of the relatively stationary member 20, and in the other direction by means including the tubular member 19 and the washer 19a associated therewith engaging with a portion of the member 20 substantially as hereinbefore described. Further, it will be noted, the tubular member 19 associated with the member 17 is freely rotatable within the relatively stationary member 21.

The tubular cup-like member 25, closed at one end thereof and provided with an auxiliary device such as an eraser 26 frictionally held therein substantially as shown, is fixedly associated with a rod-like member 27 whereby, when the member 25 is positioned within the member 17 the member 27 extends through and within said tubular member 19, it being understood of course, that the members 25 and 27 are freely slideable within the members 17 and 19, respectively, when so arranged. It will be noted that the member 27 is provided with a bent end portion 28 which, when the members 25, 27, 17 and 19 are positioned as aforesaid, is adapted to project through and slide in an opening 29 formed in said member 19. It is further to be noted that the part 28 projecting through said opening 29 is also adapted to be received in the substantially helical opening 22 formed in the relatively stationary member 21 positioned circumjacent said member 19 as hereinabove described, whereby, as the sleeve 17 is rotated alternately in different directions, reciprocating movement is imparted to the member 25, thus increasing or decreasing, as the case may be, the projecting portion of the eraser or similar auxiliary device, useful in writing, 26. It will be observed that the movement of the member 26 so produced is limited however, in an outward direction by engagement of the projecting end portion 28 of the member 27 with the washer 23, and in an inward direction by abutment of parts of the member 25 against the constricted portion 18 of the member 17.

In operation, when it is desired to advance or feed the eraser, or the like, 26, the sleeve 17 is rotated relative to the casing 15, whereby the bent end portion 28 of the rod 27 travels along the helical opening 22 in the relatively stationary member 21 thereby causing the eraser 26 to move within and project from the sleeve 17. When it is desired to replace the eraser 26, which is preferably frictionally held in the cup-like member 25, it is obvious that after removal of the used portion, a new eraser can be mounted therein merely by aligning the eraser and the opening in the member 25 and forcing the former into the latter.

It is to be understood that this improvement is capable of extended application and is not

confined to the exact showing of the drawing nor to the precise construction described and, therefore, such changes and modifications may be made therein as do not affect the spirit of the invention nor exceed the scope thereof as expressed in the appended claims. 5

What is claimed is:

1. An eraser holding device for lead pencils having a hollow casing comprising, a substantially cylindrical-shaped sleeve adapted to be supported within one end of the casing, a tube-like member extending from said sleeve, said tube-like member having a longitudinal slot in one wall thereof, a member supported in the opposite end of said casing having a reduced end and spaced from said sleeve, a hollow cylindrical-member formed with a helical groove supported within said reduced end and receiving said tube-like member therein, means carried by said sleeve for supporting an eraser, and a rod-like member extending longitudinally from said means through said tube-like member and having one end laterally extended for engagement with the helical groove whereby rotation of said sleeve will cause the supported eraser to reciprocate therein. 25

2. An eraser holding device for lead pencils having a hollow casing comprising, a substantially cylindrical-shaped sleeve adapted to be positioned within one end of the casing, a tube-like member extending from one end of said sleeve, said tube-like member having a longitudinal slot in one wall thereof, a substantially cylindrical-shaped member positioned in the opposite end of said casing and spaced from said sleeve, said cylindrical-shaped member being hollow and having one end thereof formed with a reduced opening, a member supported within said reduced opening and adapted to receive said tube-like member therein, said member being formed with a helical groove, means carried by said sleeve for supporting an eraser, and a rod-like member extending longitudinally from said means and having one end laterally extended through said longitudinal slot and adapted for engagement with said helical groove, whereby rotation of said sleeve will cause the supported eraser to reciprocate therein. 35

3. An eraser holding device for lead pencils having a hollow casing comprising, a substantially cylindrical-shaped sleeve adapted to be positioned within one end of said casing, said sleeve being hollow and having one end thereof partially closed with a hollow tube-like member projecting therefrom, said tube-like member having a longitudinal slot formed in one wall thereof, a member having a reduced end positioned in the opposite end of said casing and spaced from said sleeve, a hollow cylindrical member supported within said reduced end and being formed with a helical groove, said tube-like member being disposed within said hollow cylindrical member, an eraser holding cap slidably supported within said sleeve and having a rod-like member extending longitudinally therefrom, the free end of said rod-like member being disposed within said longitudinal slot and having its end bent at right angles for engagement with said helical groove, whereby rotation of said sleeve will cause the supported eraser to reciprocate therein. 65
